UNITED STATES PATENT OFFICE.

PETER H. SCHLUETER, OF CHICAGO, ILLINOIS.

KETTLE.

1,162,108.

Specification of Letters Patent. Patented Nov. 30, 1915.

Original application filed April 23, 1914, Serial No. 833,625. Divided and this application filed October 22, 1914. Serial No. 868,105.

To all whom it may concern:

Be it known that I, PETER H. SCHLUETER, a citizen of the United States, and resident of Chicago, county of Cook, and State of Illinois, have invented certain new and useful Improvements in Kettles, of which the following is a specification and which are illustrated in the accompanying drawings, forming a part thereof.

10 The invention relates to kettles, and has been divided out of my application for patent on cooking vessels filed April 22, 1914, Serial No. 833,625.

The object of the invention is to provide 15 a kettle in which large quantities of syrup may be quickly heated or cooled. The invention accordingly contemplates a jacketed tilting kettle having a fluid coil within its chamber, and provision for circulating a 20 heating or cooling medium simultaneously through both the jacket and the coil.

A detail of the invention provides for a rotation of the coil to further the interchangeability of heat between the jacket 25 and coil and the contents of the kettle.

In the accompanying drawings—Figure 1 is a central sectional view of a kettle embodying the features of improvement provided by the invention; and Fig. 2 is a 30 detail view of the coil with a portion of the coil broken away and the supporting shaft shown in section.

In carrying out the invention a bowl-shaped kettle 10, having a jacket 11 covering its lower portion, is preferably provided. In event the kettle is to be used for treatment of a syrup under vacuum, as in carrying out the process of making candy which is made the subject of my Patent No. 40 1,101,572, dated June 30, 1914, a hood 12 is provided, and the rims 13 and 14 of the kettle and hood are constructed for sealed engagement. Provision is also desirably made for tilting the kettle 10 upon its supports, as 15, 16.

As shown, a tubular trunnion 17 is rigidly secured against one side of the kettle 10 above the jacket 11, and extends outwardly therefrom. This trunnion is journaled in 50 the support 16. A threaded tubular nipple 18 is formed upon the inside wall of the kettle 10 in line with the trunnion 17. The bore of this nipple communicates with the bore of the trunnion. A pipe 19 also

leads laterally out of the trunnion 17, and 55 is connected with the jacket 11. Preferably this pipe is controlled by a valve 20.

A tubular bushing 21 is mounted upon the outside wall of the kettle 10 at the remote side of the kettle from the trunnion 17 and 60 in line therewith. This bushing serves for the attachment to the kettle of a tubular trunnion 22, which is journaled in the support 15. As shown, the inner end of the trunnion 22 is threaded and enters an annular socket 23 formed in the bushing 21.

The nipple 18, bushing 21, and trunnion 22 serve as journals for a shaft 24, which extends horizontally across the chamber of the kettle and carries a spirally formed pipe 70 coil 25. The end portions of the shaft 24 are made tubular, as indicated at 26 and 27, and the bores of these tubular parts of the shaft communicate with the bore of the pipe coil 25 to form an uninterrupted passage for 75 fluid from one end of the shaft through the coil and thence to a lateral opening 28 adjacent the other end of the shaft.

An annular flange or bead 29, formed upon the shaft 24 adjacent one end, contacts 80 with the end of the nipple 18, and a collar 30 is fitted about this flange and has threaded engagement with the nipple to provide a means for packing the shaft against leakage of fluid about the shaft and into the 85 chamber of the kettle.

To facilitate the assembling of the parts the shaft 24 is formed in two sections 31, 32, and these sections are united end to end by a threaded nipple 33. An annular bead 90 or flange 34, formed on the section 32 of the shaft 24 and fitting within the bore of the tubular trunnion 22, serves, in conjunction with the threaded connection of the trunnion 22 and bushing 21, to provide a means 95 for packing the shaft against leakage of fluid into the chamber of the kettle through the bore of the bushing 21.

The pipe coil 25 is rotated, independently of the tilting of the kettle 10, by extending 100 the section 32 of the shaft 24 beyond the outer end of the trunnion 22 and applying a belt pulley 35 thereto. To prevent leakage of fluid outwardly through the bore of the trunnion 22, the outer end portion of 105 the bore of the trunnion is enlarged to form a threaded socket 36, and a packing gland 37 enters this socket. The bore of the trun-

- nion 22 also has lateral openings 38 and 39, these being preferably formed in line with the lateral opening 28 in the shaft 24. One of these lateral openings, as 38, is connected 5 with the under side of the jacket 11 through a pipe 40. This pipe is desirably provided with a pet cock 41 adjacent its lower end for draining the jacket 11. The other lateral opening, as 39, is preferably connected 10 with a fluid discharge pipe 42. This discharge pipe will usually be made from flexible material, as in the form of a hose, in order that the tilting of the kettle may not be interfered with.
- 15 A nipple 43, for the attachment of a fluid supply pipe, has swiveled connection with the outer end of the trunnion 17. To prevent leakage of fluid about the nipple the inner end thereof is shouldered, as at 44, and 20 a tubular plug 45 enters the outer end of the trunnion 17 about the nipple. A nut 46, applied to the outer end of the nipple 43, serves for clamping a quantity of packing material 47 between the shoulder 44 and 25 the inner end of the plug 45. If either a heating or a cooling fluid be supplied at the nipple 43, the same may be circulated through the jacket 11 and through the pipe coil 25 while still permitting the pipe coil 30 to be rotated and without interfering with the tilting of the kettle. If desired the valve 20 may be closed, in which case the fluid will circulate through the pipe coil 25 alone. Preferably an intermediate support for the 35 pipe coil 25 is formed by mounting a spider 48 upon the shaft 24 at about the mid width of the kettle. The arms of this spider are engaged with one of the intermediate turns of the pipe coil 25.
- 40 I claim as my invention—
1. In combination, a tilting jacketed kettle having a tubular trunnion, a fluid supply pipe having swiveled connection with the trunnion, and connection between the 45 bore of the trunnion and the chamber of the jacket.
  2. In combination, a tilting jacketed kettle having a tubular trunnion, a pipe coil within the chamber of the kettle, a fluid 50 supply pipe having swiveled connection with the trunnion, and connections between the bore of the trunnion and the chamber of

the jacket and the bore of the trunnion and the pipe coil.

3. In combination, a tilting jacketed kettle having a tubular trunnion, a pipe coil within the chamber of the kettle, a fluid supply pipe having swiveled connection with the trunnion, connections between the bore of the trunnion and the chamber of the 60 jacket and the bore of the trunnion and the pipe coil, and a valve controlling one of the last-mentioned connections.

4. In combination, a tilting bowl-shaped kettle having a tubular trunnion, a helical 65 pipe coil horizontally disposed within the kettle and having intermediate turns of greater diameter than the turns at either of its ends with an end of the coil axially extended and in swiveled connection with the 70 said tubular trunnion of the kettle and means for rotating the coil.

5. In combination, a tilting bowl-shaped jacketed kettle having a tubular trunnion and connection between the bore of the trunnion and the chamber of the jacket, a helical pipe coil horizontally disposed within the kettle and having intermediate turns of greater diameter than the turns at either of its ends with an end of the coil axially extended and in swiveled connection with the 75 said tubular trunnion of the kettle, and means for rotating the coil.

6. In combination, a steam jacketed kettle having trunnions, one thereof being tubular, a steam coil within the chamber of the kettle, a steam inlet having swiveled connection with the tubular trunnion, and steam 80 passages connecting the bore of the trunnion with the jacket of the kettle and with 90 the said steam coil.

7. In combination, a steam jacketed kettle having trunnions, one thereof being tubular, a steam coil within the chamber of the kettle, a steam inlet having swiveled 95 connection with the tubular trunnion, steam passages connecting the bore of the trunnion with the jacket of the kettle and with the said steam coil, and a valve controlling one of said passages.

PETER H. SCHLUETER.
